(57) **CLAIM**

The ornamental design for a resonator coil, substantially as shown and described.

DESCRIPTION

FIG. 1 is a perspective view of a resonator coil.
 FIG. 2 is a top view of the resonator coil of FIG. 1.
 FIG. 3 is a bottom view of the resonator coil of FIG. 1.
 FIG. 4 is a right view of the resonator coil of FIG. 1.
 FIG. 5 is a left view of the resonator coil of FIG. 1.
 FIG. 6 is a front view of the resonator coil of FIG. 1; and,
 FIG. 7 is a back view of the resonator coil of FIG. 1.
 The broken lines show portions of the resonator coil that
 form no part of the claimed design.

1 Claim, 4 Drawing Sheets(56)
